UNITED STATES PATENT OFFICE.

ANTONIO CAMINITI, OF BROOKLYN, NEW YORK.

CORK-MACHINE.

1,162,567.

Specification of Letters Patent. Patented Nov. 30, 1915.

Application filed December 18, 1912. Serial No. 737,538.

To all whom it may concern:

Be it known that I, ANTONIO CAMINITI, a subject of the King of Italy, residing at Brooklyn in the county of Kings and State of New York, have invented new and useful Improvements in Cork-Machines, of which the following is a specification.

The general object of the invention is to improve and refine the construction of cork or stopper making machines and to adapt such structures for turning out corks or stoppers of non-circular contour in cross section. And to this end the invention resides in certain combinations and arrangements of parts hereinafter to be described in the accompanying specification and particularly pointed out in the appended claims, reference being had to the accompanying drawings forming one embodiment of the invention and in which,

Figure 1 is a side elevation partly in vertical section of the invention. Fig. 2 is a plan. Fig. 3 is a horizontal section on the line 3-3 of Fig. 1. Fig. 4 is a sectional detail view of parts of the machine cut on the line 4-4 of Fig. 1 and showing parts broken away. Fig. 5 is a sectional detail of the carrier. Fig. 6 is a view similar to Fig. 3 but on a larger scale and showing the parts in different position from that shown in Fig. 3. Fig. 7 is an enlarged sectional view of a beveled pinion and supporting means used in the machine. Fig. 8 is a transverse sectional view of part of the machine cut on the line 8-8 of Fig. 2. Fig. 9 is an enlarged plan view of a block delivery means used in conjunction with the machine.

Briefly stated, my invention consists in cutting a strip of cork 5 the thickness of which corresponds to the length of the finished cork, into blocks or squares 6, introducing the squares to a carrier which moves each square into contact with a knife 7 which is arranged so as to cut off or round the corners of the squares and finally introducing the squares to a grinding or finishing disk 8 which operates to remove whatever raggedness which results from the cutting by the knife 7 and to grind or even the surface of the cork or stopper.

A supporting frame, the upper portion of which is shown in Fig. 1 and indicated by 9, is attached to a suitable base (not shown). The lower portion of this frame (not shown) carries suitable driving shafts (not shown) which are operatively connected in any well known manner to the circular knives 7 and 10 and to a vertical shaft 11 also journaled in the frame 9 and in a superstructure 12 arranged on one end portion of the said frame. A disk 13 is suitably fixed to the upper end portion of the shaft 11 beyond the superstructure 12, such as by a contractile sleeve 14, and this disk carries an eccentrically disposed wrist pin 15 arranged for radial adjustment in a slot 16' in the disk and forming a bearing for one end of a connecting rod 16 whose length may be varied by a turn-buckle 17 to compensate for an adjustment of the wrist pin to a position nearer the center of the disk than shown in Figs. 1 and 2, and which connects the said disk with a crank arm 18 that provides a support or carrier for a pawl 19.

A shaft 20 has one end held in a bearing 22 in the frame 9 and its upper end portion extending through and beyond the superstructure 12 and loosely fitted in the crank arm 18. A sleeve 23 loose upon the shaft 20 has fixed to its upper end and directly beneath the crank arm 18 a ratchet 24 whose teeth are so disposed as to be successively engaged by the pawl 19 when the said pawl is moved in one direction. Arranged on the sleeve and located below the superstructure 12 is a bevel gear wheel 25 whose teeth mesh with a plurality of bevel pinions 26-26 arranged between the arms of yokes 27-27 which are arranged upright and secured by suitable fastening means such as by screws 28, to a table 29 which has an enlarged central opening 30 for the sleeve 23.

Below the table 29 is a vibrator herein shown as including a disk 30' fixed to the sleeve 23 and an annular member 31 screwed or otherwise suitably fastened to the disk and having a depending portion 32 the inner surface of which is corrugated as indicated at 33 in Fig. 4, or otherwise suitably formed so as to impart a reciprocating or vibrating

motion to a series of rolls 34 which are arranged on pins 35 disposed in arms 36 and angular projections 37 of a carrier.

In addition to the arms 36 the carriers 5 consist of a wheel 38 whose hub 39 is fixed to the shaft 20 and disposed below the depending portion 32 of the vibrator. The arms 36 are disposed between the radial guides 39' of the wheel and are arranged so 10 as to have the rolls 34 in horizontal alinement with the corrugated surface 33 of the vibrator into which surface the rolls are held by compression springs 41 which bear on a bushing 42 and on the angular projections 37 of the arms, the arms being of such 15 length that a space will exist between their inner ends and the shaft 20 when the rolls are in the furrows of the corrugated surface 33, all of which is shown in Figs. 1 and 20 5. The bottoms of the guides which support the arms 36 have cut-away portions in which are arranged blocks 43 held by suitable fastening means, such as bolts 44, and carrying bracket arms 45 to which are pivoted 25 rock arms 46 the inner end portions of which are normally depressed by compression springs 47 which are connected to blocks 48 arranged in cut-away portions inwardly of those which receive the blocks 43 30 and secured by suitable fastening means, such as bolts 49. The outer ends of the arms 36 are each provided with superimposed yokes 50 and 51. The spindles 52 are journaled in the arms of the yokes 50, their 35 lower ends extending below the lower arms of such yokes and having fixed thereto disks 53 whose lower surfaces are barbed. Bevel gears 54 are fixed to the spindles between the arms of the yokes 50 and mesh with 40 bevel gears 55 connected to shafts 56 journaled in upright portions of the yokes 50 and slidingly fitted in the yokes 27 and in the pinions 26. As shown in Figs. 1 and 7 ball clutches 57 are employed for connecting 45 the pinions 26 with the shafts 56, the balls of such clutches being set in longitudinal grooves in the shafts 56, whereby to prevent independent turning movement of the pinions and shafts, but permitting of longitudinal 50 movement of the said shafts 56. The spindles 58 are arranged for turning and sliding movements in the lower arms 59 of the lower yokes 51, the upper end portions of such spindles having disks 60 with barbed 55 surfaces in vertical alinement with the barbed surfaces of the disks 53. The collars 61 loosely receive the lower end portions of the spindles 58 but are held against longitudinal movement on the said spindles and 60 are connected to the stirrups 62 at the outer ends of the rock arms 46.

A ratchet 63 is fast upon the shaft 20 and located a trifle above the bearing 22 and directly below a lever arm 64 loose upon the

shaft 20 and carrying at its outer end a wrist pin 65 on the lower portion of which is arranged a pawl 66 for engaging the teeth of the ratchet 63, successively. A connecting rod 67 rendered extensible by a turn buckle 68 connects the upper portion of the wrist 70 pin 65' on the arm 64 with one end of a pitman 69 whose opposite end is connected to a portion of the frame 9 as shown in Fig. 3. A roller 70 on the pitman 69 is arranged in the path of movement of a cam 71 on the 75 shaft 11 so that upon the cams contacting with the roller 70, the pitman 69 will be moved outwardly or to the left in Fig. 3 thus transmitting movement to the ratchet through the connecting rod and pawl. A 80 spring 72 surrounding the pin 73 which connects the pitman to the frame, is arranged so as to be contracted or tensioned upon the outward movement of the pitman, whereby to restore the pitman and the pawl to their 85 normal positions upon the moving of the cam away from the roll 70.

74 is a toothed disk fast upon the shaft 20 and arranged above the ratchet 63. A dog 75 pivoted to one side of the frame 9 90 and inwardly from the shaft 11, is arranged to coöperate with any of the notches in the disk to control the movement of the shaft 20 with the parts fastened thereto. A spring 76 surrounding the pivot of the dog 95 75 is arranged so as to normally hold the dog in engagement with the disk. The dog is operated to engage the disk by a link 77 which is connected to the dog by pin and slot connections 78 and which slides 100 upon an inwardly directed angular extension 79 on one side of the frame 9. A lever 80 is pivotally mounted in a bracket 81 on the frame 9 and located above the horizontal plane of the cam 71. This crank is connected to one end of the link 77 and is operated by a spring 82 so as to normally hold the link in the position shown in Fig. 3, where it is seen that the link in this position effects the locking of the disk 74 by 110 the dog 75. The free end portion of the lever 80 extends into the path of movement of a cam 83 on the shaft 11, which cam is proportioned so as to effect during one revolution of the shaft, the outward movement of 115 the lever 80 and the disengagement of the dog 75 from the disk 74.

The frame extension 79 is provided with a quadrantal cam 84 arranged in the path of movement of the rollers 85 on the inner 120 ends of the rock arms 46. One end of this cam 84 is beveled so as to admit of the rollers 85 riding upwardly thereon when the carrier is moving in a clockwise direction. The link 77 is provided with a lateral extension 86 that supports a projection 87 that forms a regular continuation for the cam 84 when the parts are positioned as shown 125

in Fig. 3, but which moves out of alignment with the cam 84 upon the movement of the link 77 to the left in Fig. 3.

A bracket 88 is suitably connected such as by pin and slot connections 89, for vertical adjustment on the frame 9. A table or platform 90 supported by the bracket 88, has a slot 91 for the passage of the knife 10. A feed device in the form of a slide 92 5 and a guide 93 are associated with the table 90, the said slide being located in a longitudinal groove 94 of the table and having its movement in the said groove controlled in one direction by an adjustable stop in the 10 form of a bolt or pin 95. The guide 93 is connected to one end of the slide 92 and has a relatively generous bearing surface 96 for the strip 5 of cork or other suitable material to be cut and also has a slot 98 in direct 15 alignment with the knife 10.

Superimposed on the table 90 and located to one side of the knife 10, is a trough the upright side portion 99 of which is fixed, while the opposite side portion 100 is connected to brackets 101 which are adjustably 20 connected to the table by screw and slot connections 102. The brackets 101 have inwardly directed extensions 103 which support a guide strip 104 extending over the 25 middle of the trough whereby to prevent upward movement of the pieces of cut cork 105 located in the trough. The trough at one end opens into the space flanked on one side by the guide 93 and its opposite end has 30 arms or extensions 106 and 107. A roll 108 is interposed between the extension 106 and the side 100 of the trough and a projection or stop 109 is arranged on the outer end of the extension 106 and in the positions shown 35 in Figs. 1 and 2. The extension 107 is pivotally connected to the upright side 99 of the trough and a spring 110 tends to force the extension 107 inwardly, whereby to effect contact between the rolls 111—111 and 40 the innermost piece of cork.

In assembling the machine the parts are so adjusted that the cam 83 will effect the disengagement of the dog 75 from the disk 74 prior to the time that the cam 71 is in 45 position to operate the pawl 65 and advance the ratchet 63 and by virtue of the relative positions of the cam 83 and wrist pin 15, the latter will begin moving in a direction that will effect the retracting of the pawl 19, 50 that is to say, the pawl will be moved to the right in Fig. 2 at substantially the same time as contact is effected between the cam 83 and the lever 80, but inasmuch as an amount of lost motion will be had by the 55 link 77 prior to the moving of the dog 75 the parts operated through the connecting rod 16 will be at rest before those parts controlled by the pawl 65 are set in operation. Owing to their relative sizes in point of ra-

dius the peripheral speed of the cam 71 will 65 be greater than the disk 13, therefore the parts operated through the cam will move at a greater speed than those operated through the disk, but owing to the difference in construction of the cam and disk the 70 duration of movement of the parts connected to the disk will be longer than those operated by the cam.

In operation, the strip 5 is arranged on the table 90 and adjusted so as to bear on 75 the surface 96 of the guide 93. The guide 93 is then moved outwardly by hand for a distance sufficient to admit of passing the strip 5 between it and the knife 10. The end of this strip is then adjusted to align with the 80 inner surface of the side 100 of the trough after which the guide is pushed in a direction to introduce the cork to the knife and the pushing continued until the knife is passed through the cork and entered the 85 recessed portion 98 at which time the end of the slide will be in contact with the bolt 95 (assuming that the said bolt has been properly adjusted) so that further movement of the guide is prevented. It will be observed 90 that the aforesaid movement on the part of the guide advances the piece cut from the strip 5 into the trough and beneath the guide 104 so that when the necessary piece 95 is cut from the strip the entrance of such 100 piece into the trough will advance the first piece toward the opposite end of the trough. This feeding or advancing of the cut pieces continues until the first piece is in the position shown in Fig. 2 and here it will be observed that the piece is held by the extension 106 and the spring action of the extension 107. The extension 107 yields as the 105 said piece is being forced over the circular portion 108 of the extension 106 and the rolls 111—111, but moves inwardly and holds the cut piece as shown in Fig. 2 when the said cut piece passes the extension 108.

Referring now to Fig. 1 for a view of the position of the parts and assuming that the 110 cam 83 is about to contact with the lever 80, the pawl 19 about to be retracted and the roller 85 bearing on the extension 87 of the quadrantal cam 84, in this position of the parts it will be observed that the cam has 115 effected the rocking of the arm 46 so that the spindle 58 is moved downwardly and a relatively wide space is presented between the disks 53 and 60. Now since this downward movement on the part of the spindles 120 58 can take place only when the spindles 52 and 58 are moving into a position in alignment with the outermost piece of cork and further since the throw of the pawl is sufficient only to move the yoke indicated by γ 125 in Fig. 2 from the position shown, into that occupied by the succeeding yoke indicated by α in each step, then when it is remem-

bered that upon the beginning of contact between the cam 83 and lever 80 the retracting of the pawl is being effected, it will be further observed that the extension 87 of the 5 quadrantal cam will be moved to the position shown in Fig. 5 upon furthr movement of the cam 83. The withdrawing of the extension 87 trips the rock arm 46 and this effects the upward movement of the spindle 10 58, which spindle, like the spindle 52 being in alinement with the outermost piece of cork, effects contact between the disk 60 and the lower end of said piece of cork with the result that the cork yielding to the upward 15 movement of the spindle is clamped between the disks 53 and 60. Upon the clamping of the piece of cork the cam 83 will have effected the unlocking of the disk 20 74 and the cam 71 will begin to operate on the lever 69. This will have the effect of 25 operating the pawl 65 to advance the ratchet 63 and effect the turning of the shaft 20. Since the carrier is fast on the shaft the turning of the latter will move the carrier for an angular distance in proportion 30 to the throw of the pawl 65 and since the parts are so proportioned as to have the throw of the pawl bear a certain relation to the distance between the center of the piece 35 of cork shown in Fig. 2 and the edge of the knife 7, it will be manifest that at the end of the angular movement of the pawl the carrier will have been moved so that the part indicated by *x* in Fig. 2 will occupy 40 the position of the part indicated by *z*. Now since the knife 7 is arranged substantially tangential to the disks 53 and 60, it will be manifest that upon contact between the knife and a section of the cork projecting beyond the disks that such section will 45 be cut by the knife. Now when it is remembered that the dog 75 will be released before the end of the turning movement of the ratchet 63, it will be seen that at the end 50 of the turning movement of the ratchet the dog will move into one of the notches of the disk 74 as shown in Fig. 3 and when it is further remembered that the pawl 19 is being retracted during the movement of the ratchet 63 then it will be manifest that the 55 said pawl 19 will be positioned to operate the ratchet 24 only after the ratchet 63 has come to rest and the disk 74 locked by the dog 75. Now upon engagement between the 60 pawl 19 and the ratchet 24 and movement of the pawl in a direction indicated by the arrow in Fig. 2, the ratchet with the parts connected thereto will be rotated. This will effect the turning of the bevel gear wheel 25 and the rotation of the cork before the knife through the connection between the spindles and wheel 25. Now, remembering that the disk 42 which is included in the vibrator, is connected to the sleeve 23 it will be seen 65 that when the sleeve rotates and turns the

cork the vibrator will act upon the arms of the carrier and effect the reciprocation of such arms in their guides. This action on the part of the arms will move the piece of cork into and out of the path of the knife 7, 70 and when the piece of cork is positioned as shown in Fig. 2, outward movement on the part of the arm indicated by *x* will arrange one of the corner portions of the piece in the path of the knife when the said arm *x* occupies the position indicated by *z* in the same figure. Now the turning of the piece of cork will effect the cutting or rounding of one of the corners thereof by the knife 7. Upon the rounding of such corner the arm is 75 retracted by the vibrator and upon further turning of the cork the succeeding corner is brought into the position first occupied by the rounded corner and at such time as the arm is fully projected, whereupon the 80 rounding or cutting of the second corner will be had. This will continue until the four corners are cut or rounded, at which time the pawl 19 will have begun its re- 85 tracting movement and the pawl 65 positioned to move the ratchet 63. After the clamping of the cork by the disks 53 and 60, the projection 107 will yield outwardly on the beginning of movement on the part of the carrier, and thus liberate the cork from 90 the trough. After the operation on the cork by the knife 7 the arm indicated by *z* in Fig. 2 will be advanced to that indicated by *v* in the same figure and the arm indicated by *x* will occupy the position of that indicated by *z*. The third step of the carrier will advance the arm indicated by *v* to the position indicated by *w* in Fig. 2 and the fourth step will bring the arm into the position indicated by *r* in Fig. 2 and into contact with the abrading wheel 8. Here the arm will vibrate the cork as before and the turning of the abrading wheel 8 will effect the grinding or finishing of the cork. The next step will advance the arm indicated by 100 *r* in Fig. 2 to that indicated by *y* in the same figure, and during the sixth or last step, the roll 85 on such arm will lower the spindle 58 thus leaving the cork in a position to drop from the disk 60 or to be removed 105 therefrom by abutting with the projection 106 whereupon the cork will fall into a suitable receptacle.

What is claimed as new is:

1. A many spindle pattern governed 120 lathe, comprising a rotatable carrier, and means for intermittently rotating the same, a plurality of spindles mounted on frames radially slidable in said carrier, intermittently rotating means concentric with said 125 carrier comprising a pattern surface for radially reciprocating said spindle carrying frames and rotating said spindles during the interval in the rotation of the carrier.
2. A many spindle pattern governed 130

lathe, comprising a rotatable carrier, means for intermittently rotating the same, a plurality of spindles mounted on frames radially slidable in said carrier, intermittently 5 rotating means concentric with said carrier for rotating said spindles during the interval in the rotation of the carrier, said means comprising an annular cam pattern surface

for radially reciprocating said spindle carrying frames. 10

In testimony whereof I affix my signature in presence of two witnesses.

ANTONIO CAMINITI.
